UNITED STATES PATENT OFFICE.

WILFRED CHARLES TRAHER, OF LONDON, ONTARIO, CANADA.

MUSIC-LEAF BINDER.

Application filed June 21, 1919. Serial No. 305,774.

To all whom it may concern:

Be it known that I, WILFRED C. TRAHER, a subject of the King of Great Britain, and a resident of London, in the Province of 5 Ontario, Dominion of Canada, have invented new and Improved Music-Leaf Binders, of which the following is a full, clear, and exact description.

My invention relates to music leaf binders, 10 my purpose being to provide a device of this character containing a number of improvements among which are the following:

I. To give the music leaf binder a rigid and substantial back adapted for expansion 15 in order to accommodate a varying number of music leaves and which is not likely to sag or to lose its shape when holding a relatively large quantity of the leaves.

II. To specially adapt the back so that a 20 cover either limp, semi-limp, or stiff, may be readily attached to it.

III. To provide a cover whether limp or stiff with a pocket of approved construction and adequate size to contain all materials 25 necessary for repairing, reinforcing, and inserting music or other papers and holding them securely.

IV. To provide reinforcing members of 30 such form that they may be conveniently cut out of a continuous strip so as to use the latter economically—this is, without waste in cutting.

V. To provide wire-retaining strips of 35 such form as to enable any person unskilled in bookbinding to easily and quickly remove any sheet or leaf of music without disturbing those already bound.

VI. To provide a cover having no metal 40 parts or laces exposed upon the outside, so as to scratch a piano or desk.

VII. To give the binder such form that 45 sheets bound in it may be opened perfectly flat.

VIII. To give the binder such form that 50 its parts may be manufactured and put together very cheaply.

IX. To provide means for reinforcing the 55 sheets or leaves with linen fabric and for sewing the same with wire so that they can not easily be torn out.

X. To provide various other improvements in construction in order to increase efficiency of the binder.

Reference is made to the accompanying

drawings forming a part of this specification, it being understood that like characters of reference indicate like parts throughout the several figures. 55

Figure 1 is a plan view of one form of 60 my improved music binder showing the same as opened and ready for use but containing no music leaves;

Figure 2 is an end elevation of the mechanism shown in Figure 1;

Figure 3 is a section on the line 3—3 of 65 Figure 1 looking in the direction indicated by the arrows;

Figure 4 is a section corresponding in position to the section shown in Figure 3 but showing certain parts as occupying different 70 positions than those they occupy in Figure 3;

Figure 5 is a section on the line 5—5 of 75 Figure 1 looking in the direction indicated by the arrows;

Figure 6 is a fragmentary plan view of 80 a pair of the reinforcing members as used together;

Figure 7 is a fragmentary plan view of 85 a single reinforcing member occupying a different position from that of the reinforcing member shown in Figure 6;

Figure 8 is a section on the line 9—9 of 90 Figure 6 looking in the direction indicated by the arrows;

Figure 9 is a section on the same line as 95 Figure 8 but showing certain movable parts as occupying positions different from those they occupy in said Figure 8;

Figure 10 is a fragmentary plan showing 100 a fastening button of a slightly different form from those appearing in other figures;

Figure 11 is a section on the line 11—11 of 105 Figure 10 looking in the direction indicated by the arrows;

A pair of boards 12, 13 each having substantially the form of a leaf is connected together by a flexible strip 14 and by a lining member 15. The flexible strip 14 carries a 110 pair of spacing blocks 16 of approximately obtuse angled sector-shaped cross section, but with one side or radius longer than the other and the extremities connected by a curved line or surface such that when the 115 blocks or sections 16 are disposed together they form a member of substantially semi-elliptical cross section, as shown particu-

larly in Figure 3 of the drawings, said blocks being faced with a lining strip 17. The blocks are further provided with an additional lining or binding over the lining 17, 5 said binding covering the opposed faces of the blocks 16, as shown at 15^a and 16^a in Fig. 4. Eyes are shown at 19, 20 mounted in opposed spaced relation on the blocks 16 adjacent to the curved, rounded or convex 10 outer faces thereof and threaded through these eyes is a lace 22 which detachably engages a button 21 at the ends as indicated more particularly in Figure 1 so as to provide spaced parallel portions between said 15 opposed eyes at the ends and longitudinal connecting portions between the eyes 19 and the eyes 20. I provide a pair of retaining strips 23 each made of wire and having the form of a pair of loops. A pocket is shown 20 at 24 and is adapted for carrying the various materials and appliances used in connection with my device. The pocket is closed by a means of buttons 25, and may have an inner portion 24^a as indicated in Figure 5. Each 25 button 25 is provided with a base 27 to which it is secured after the manner of a snap fastener and the latter is mounted on a reinforcing member 28 as shown in Figure 5. As illustrated, this reinforcing member 28 30 is in the form of a strip carried by the board 13 beneath the covering thereof.

Three music leaves are shown at 29, 30 and 31, the leaves 29 and 31 being in this 35 instance integral with each other and the leaf 30 being a so-called single or intermediate leaf. Reinforcing strips are shown at 33, 34, 35 and each is of a substantially diamond shape as may be understood from Figures 6 and 7. These reinforcing strips 40 may be cut from a continuous strip of gummed linen, say thirty-six inches long, these strips being cut diagonally across so as to save the material. In this manner a strip of given length can make a comparatively large number of the reinforcing diamond-shaped strips. In order to insert the 45 double sheet consisting of the leaves 29, 30, I open the binder and lay the sheet across it in such manner that portions of the lace 50 22 between the eyes 20 are readily located. I mark the places where the laces touch the leaves. I then take this sheet, place it on other sheets to be inserted and straighten them all, bringing them edge to edge. I 55 next bring their backs to the edge of a table and with a penknife I mark all of the sheets. This is done by a downward stroke of the knife and marks each sheet where the 60 laces will touch it. The result is that a small cut will be noticeable on the inside of the sheet when folded.

I then open each sheet and stick one of the reinforcing strips 33, 34 over the small cut made therein and just described. I 65 next fold the sheets and with the point of a

pair of scissors or a penknife cut a small notch or hole at the points where the mark has already been placed by the penknife as above described. This done with the sheets lying on the binder, I grasp the retaining strip 23 of wire and pass it upwardly through the holes thus cut and which are shown at 22^a. The wire strip is thus used as a needle and by drawing it through as indicated in Figure 9 the lace is brought upwardly through the holes. This done, the wire strip is turned slightly and thus disposed directly across the adjacent portion of the lace as indicated in Figure 1, the lace thus resting between the two loops of wire. The laces are drawn taut and secured to the button 21. This holds the sheets firmly in position. Where the intermediate sheet 30 is used reinforcing strips 35 are pasted partly upon the single or intermediate sheet 30 and partly upon the leaf 31 of the double sheet as indicated in Figures 8 and 9. Thus, the intermediate sheet 30 is secured in position between the leaves of the double sheet as indicated in these figures.

In some instances the pocket 24 may not be used. In cases of this kind a button 38 is mounted upon a flexible strip 36, the latter being reinforced by a portion 37 of the lining and secured firmly to the board 13 as shown in Figure 11. The lace is secured by drawing its ends around the button 38.

I do not limit myself to the precise mechanism shown as variations may be made therein without departing from the spirit of my invention.

Having thus described my invention what I claim as new and desire to secure by Letters Patent is as follows:

1. In a binder, a pair of cover leaves, a flexible strip connecting said leaves, spacing blocks of approximately obtuse-angled sector-shaped cross section secured with their rounded faces extending longitudinally of said strip so as to nearly fill the space therebetween when folded and movable relatively to each other into and out of contact in order to permit the cover leaves to be moved apart in order to accommodate different thicknesses of leaves, and means for securing said last-named leaves in position.

2. In a binder with a pair of boards serving as backs, and a pair of spacing blocks therebetween, a flexible sheet connecting the boards and engaging the blocks, a plurality of screw eyes carried by each of the blocks, a flexible strand threadedly engaging said screw eyes, means carried by one of the backs for securing the lace when the same is drawn taut so as to span the back, and reinforcing members each made of a straight section of wire and having its ends bent into relatively closed loops to engage the lace to hold music leaves in engagement with said lace.

3. In a binder having backs and a binding, the combination of a lace for holding music leaves and disposed across the binding, a wire member in the form of a single length bent to form loops at its ends with the inner ends of the loops disposed closely adjacent each other and adapted to be threaded through a hole in the music leaves, said wire member being of such form that after being threaded through said hole it 10 may be disposed crosswise of said hole and in such relation to said lace as to be held thereby against longitudinal movement.

WILFRED CHARLES TRAHER.
